TYPEWRITING MACHINE

John Teggenburger, Bogota, N. J., assignor to
Underwood Elliott Fisher Company, New
York, N. Y., a corporation of Delaware

Application November 25, 1929
Serial No. 408,511

3 Claims. (Cl. 107—126)

This invention relates to web-manifolding typewriters, in which is used a carbon-pack in the form of a girdle that is shiftable along the web. Girdles of this kind are shown in the Johnson Patent, No. 1,736,535, dated November 19, 1929, and the Crews Patent No. 1,565,550, dated December 18, 1925.

The carbon pack or set travels with the web at the line-feeding operation; and as soon as the 10 typing of the form is completed the multiple-ply web is advanced, while the carbons are restrained, thus effecting a carbon-stripping operation, which brings the carbons into corelation with the succeeding form on the web, preparatory to typing the same.

According to one feature of the present invention, a carbon pack, unit or set engirdles the web, and includes a carbon carrier or backing which has transverse slits near its leading end, 20 the plies of work-web being threaded through said slits, one ply in each slit. The web-plies are pulled through the slits at the carbon-stripping operation; but at other times the web and the carbon-unit travel together, the carrier being a 25 flexible sheet adapted to run around the platen. By means of said slits there is formed a set of transverse bars in the carbon-carrier, and from these bars the carbon-sheets extend towards the delivery side of the platen.

30 At its other end the flexible carbon-carrier is caught upon an anchorage in the form of a bar which is fixed upon the platen-frame, so that this end of the carrier is retained in stationary condition or anchored during the carbon-stripping 35 operation. The carbon-carrier sheet is made of great length, so that it can reach beneath the platen and up in front thereof, thereby permitting the carbons to become straightened out at the delivery side of the platen preparatory to the 40 stripping operation, thus avoiding binding between the web-plies and the carbons.

After the stripping operation, the platen is rotated backwardly to bring the bottom of the typed 45 form to a web-severing knife, whereby the typed form may be torn off. At this time the web is preferably in position to receive the first line of typing on the succeeding form.

During the above-described retraction of the 50 composite web, the carbon-carrier sheet remains with its rear end attached to said transverse bar. Consequently the free portion of the carrier-sheet 55 idly forms itself into a loop at the back of the platen. This loop is partly taken up as the line-spacing proceeds during the typing of the next form. After the latter is typed, the bottom feed-rolls are cast off from the platen, and the leading 60 end of the web is grasped between the fingers and pulled up. By this operation there is first taken up the remaining loop or slack in the carbon-car-

rier, and then the webs are stripped past the carbons as far as required.

Other features and advantages will hereinafter appear.

In the accompanying drawing, 63

Figure 1 is a perspective view, showing the carbon-unit in place in the machine, and illustrating the method of attaching the rear end of the carbon-carrier to its anchorage, but omitting the work-webs.

Figure 2 shows another method of attaching the carbons to the flexible carbon-carrier, in which the carbons are provided with shoulders which are stitched to the side-edge portions of the flexible carbon-carrier sheet.

Figure 3 is a sectional side elevation of a platen-carriage of an Underwood typewriting machine, illustrating the present invention, with the parts in positions for tearing off a typed form; the carbons being shown as having been 80 stripped to the next form.

Figure 4 is a perspective front view, illustrating the manner of stripping the carbons as the latter are held by their anchorage.

In said machine, types 10 strike against a platen 85 11, having an axle 12, whereby it is mounted in the ends 13 of a platen-frame, the latter including a rear paper-shelf 14 extending upwardly and rearwardly from the bottom of the platen.

The plies of work-web 15 are introduced at the 90 back of the machine and led forwardly over the paper-shelf 14 and down around the platen and up in front thereof, where they may be guided by a delivery chute 16 having guides 17 for the opposite side edges of the web; said chute including a delivery table 18 which extends upwardly and rearwardly from the delivery side of the platen.

Between the plies of web are interleaved carbon-sheets 19, which are free at their leading 100 ends, but which at their trailing ends are attached to a flexible carrier in the form of a sheet 20 of smooth, durable fabric, which may pass readily around the platen, but is capable of exerting control over the carbons. The carbons may 105 be individually attached at their trailing ends to cross-bars 21, which are formed in the advance portion or end of the carbon-carrier 20; the latter having sufficient stiffness and the bars 21 being of sufficient height to form firm attachments or supports for the carbons.

The bars 21 may be formed by cutting transverse slots 22 in the carrier; and the trailing ends of the carbons may be cemented or otherwise attached to the bars, or folded thereover.

The web-plies 15 are threaded through the slots 22, one ply through each slot, and the carbon-carrier sheet 20 may be sufficiently smooth to avoid undue friction when the web-plies are drawn through the slots at the carbon-stripping 120

operation. At other times the carbon-unit and the web run together around the platen, being held thereagainst by the usual feed-rolls 23, which are shown released at Figure 4, for the carbon-stripping operation. It will be seen that the carbon-set, which includes the carbon and the carrier 20, engirdles the web and travels therewith, but that relative shifting can take place lengthwise of the web.

10 At its rear end the carbon-carrier sheet 20 is attached to a transverse bar 24, which is fixed at its ends to the top of a pair of arms 25 erected at opposite ends of the platen frame or carriage. A clip 26 is pivoted at 27 upon one end of said bar, and clips the folded end of the flexible carbon-carrier 20 over the bar; anchoring the carrier firmly at all times. The device is particularly useful at the carbon-stripping operation, since the sheet is firmly held at all points while the web is being pulled past the interleaved carbons. The tendency of the work-web at this time is to effect a straightening out of the carbon-unit, because the latter is fixed at its rear end while the work-web advances therethrough, and, by friction, tends to pull the carbon-carrier taut at all points, therefore bringing it into proper lateral position; the work-web being guided by the chute 16, and at the conclusion of the stripping operation carbons are found to have the proper registration with reference to the work-web.

15 The stripping is completed by the time the web is raised to the Figure 4 position. Thereupon the platen is rotated backwardly by means of a hand-wheel 28; the feed-rolls 23 having first been restored to the platen. This retraction proceeds until a perforated line 29, which separates the forms, reaches the edge of a knife 30, whereupon the typed form is torn off at Figure 3. At this time the web is in position for typing the first 20 line upon the succeeding form.

25 The knife 30 is securable at any elevation in a rack 31 that is formed upon side plates 32; the arms 25 extending up from said side plates and a pair of base flanges 33 being bent out from the plates 32 for attachment by screws 34 to the tops of the platen-frame ends. It will be seen that the plates 32 are rigidly joined by the bar or tie-rod 24, and also that the racks 31 are rigidly joined by a tie-bar 35; thus making a frame which 30 carries the adjustable knife 30, so that the whole device may be manufactured as a unit for attachment to standard Underwood and other typewriters. Said knife is adjustable up and down in notches 36 and threaded holes 37 provided in said racks.

35 To accommodate different widths of paper, the side guides 17 may be formed upon separate plate-portions 38 of the chute, Figure 1, the plates 38 being adjustably held by screws 39 upon the tie-bar 35.

40 At Figure 2, the carbons 40 have projecting portions or shoulders 41 at their trailing ends, and these shoulders are attached by lines of stitching 42 to the leading portion 43 of the carbon-carrier, said leading portion being cut away or recessed at 44 to great depth, to expose a great area of the lower portions of the carbons to the type-blows; thus conducing to efficiency and economy.

45 The plies of work-web are inserted between the carbons 40 before the carbon-carrier is attached to the machine; and the same practice is also observed with the form of the invention shown at Figure 4.

50 It will be seen that the carbon-carrier, although one portion thereof travels with the web during

the line-spacing operation, is fixed to the platen-frame at its rear end, so there is no danger of the carbon-carrier becoming skewed or buckled, nor liability of the carbons becoming either skewed or creased. The carbon-carrier receives the same longitudinal tension at all portions of its width, and is not liable to become torn or injured. It will also be seen that the carrier is readily attached along its entire length to the platen-frame, and hence the carbons will automatically become realigned at the stripping operation, in case they have become disarrayed during the line-feeding. Skewing and side pull of the carbons is prevented, and side guides for the carbons may in many cases be omitted. No strain is put upon the flexible carrier at any point where it is fastened to the typewriter.

55 Another valuable feature is that at any time the carbon-carrier may be released from the anchorage 24, and shifted a little in a direction longitudinal of the work-web, thereby exposing fresh lines or portions of the carbon for use. This conduces to efficiency and effects substantial economy of carbon-paper in many kinds of work. Many other advantages are also apparent from 60 the foregoing description and drawing.

65 No claim is herein made to the inventions disclosed in the co-pending application of Jesse A. B. Smith, Serial No. 315,548, filed October 27, 1928, or Serial No. 358,173, filed April 26, 1929, renewed November 12, 1931. The claims in this case are limited to features which are not disclosed in either of said applications.

70 Variations may be resorted to within the scope of the invention, and portions of the improvements may be used without others.

Having thus described my invention, I claim:

1. As a new article of manufacture, a carbon-pack forming a unit and including a flexible carrier-sheet, and carbon-sheets extending from the leading end of the carrier, the other end of said carrier being adapted for attachment to an anchorage in a typewriting machine, the carbon-sheets having shoulders which project beyond the sides of the work-plies, and said shoulders being attached to the front end of the carrier-sheet, said front end having a deep recess to expose additional portions of the carbon-sheets to use.

2. A web-manifolding attachment for a typewriting machine in the form of a unit, including a frame having means for attachment to the platen-frame of a typewriting machine, said frame including a tie-bar which serves as an anchorage for attachment thereto of the rear end of a carbon-carrying sheet, said frame also having a web-severing knife extending from side to side of the frame, the latter having racks upon which the ends of the knife are adjustable up and down.

3. A web-manifolding attachment for a typewriting machine in the form of a unit, including a frame having means for attachment to the platen-frame of a typewriting machine, said frame including a tie-bar which serves as an anchorage for attachment thereto of the rear end of a carbon-carrying sheet, said frame also having a web-severing knife extending from side to side of the frame, the latter having racks upon which the ends of the knife are adjustable up and down, said frame also having a laterally-expansible web-chute at the delivery side of the platen.
